UNITED STATES PATENT OFFICE.

WILLIAM H. TRISSLER, OF CLEVELAND, OHIO, ASSIGNOR OF ONE-HALF TO
JOHNATHAN P. ABBOTT, OF SAME PLACE.

CARPET-CLEANER.

SPECIFICATION forming part of Letters Patent No. 371,109, dated October 4, 1887.

Application filed April 9, 1884. Serial No. 127,242. (No model.)

To all whom it may concern:

Be it known that I, WILLIAM H. TRISSLER, of Cleveland, in the county of Cuyahoga and State of Ohio, have invented certain new and 5 useful Improvements in Carpet-Cleaning Machines, of which the following is a specification.

My invention relates to carpet-cleaning machines; and it consists in the improvements hereinafter described and set forth.

10 In the accompanying drawing the figure represents in perspective a carpet-cleaning machine constructed in accordance with my invention.

The machine consists of a triangular-shaped 15 cage made of slats A and provided with trunnions C, set in boxes supported by any suitable frame-work, and having a driving-wheel, D, for giving rotary motion to the same. The ends or heads of said cage are made of slats a, 20 which are arranged so as to leave openings between the same, and are secured in this form, so as to give strength and stiffness. The said slats a are extended at one end, so as to present the side portions for pockets or sub-chambers 25 B, each of which is of triangular form, as represented in the accompanying drawing. Each pocket B is so arranged relatively to the cage that each of the triangular pockets does not drop the carpet therefrom until the triangle 30 constituting the pocket B arrives at a vertical position.

E refers to a door through which the carpets are introduced into the machine.

By having the cage of the triangular form 35 described the carpet falls the greatest width or diameter of the triangle, so as to be most effectively cleaned in its movement.

With all the other forms of carpet-cleaning 40 machines with which I have been acquainted the sides and pockets have been so arranged as to intercept the fall of the carpet before it had traveled a proper distance, which necessarily prevents the carpet leaving the dust which has been beaten out of it.

I am also aware that the triangular form has 45 heretofore been used in coal screens or sifters; but in such construction for that purpose no pockets are employed, nor is the result of the operation of the machine the same. In such screens and sifters the ashes, coal, &c., being 50 separate particles and not a connected mass as a carpet, do not receive the long falls across the cage that the carpet does, nor do they require it.

I would not be understood as claiming, broadly, the triangular form of cage, as in order to make it efficient the pockets must be 55 added in the angles, which cause the carpets to be carried clear up to the highest point and then dropped across the entire width of the cage each time.

I am also aware that the pockets, broadly, are not new. They have been added to the four corners of the rectangular cages; but in such cages they do not possess the advantages which their addition to the triangle insures. 65 In the rectangular cage they bear such a relation to the revolving side walls as to cause the cage to dump its contents before it reaches the highest point, and at the same time the side walls of the cage are not in position to receive 70 the carpet or to allow it to fall entirely across the width of the cage, as the construction I show and claim would do.

I claim—

The combination, in a carpet-cleaning machine, of a cage or body of triangular form and composed of open slats, as described, the open slats of the heads being trussed and extended beyond the triangle, horizontal slats combined therewith to present triangular pockets B, and 80 trunnions and driving-wheel, substantially as set forth.

WILLIAM H. TRISSLER.
